UNITED STATES PATENT OFFICE

124,814

DESIGN FOR A FITTING FOR ENGINE BREATHER SYSTEM

Adolph C. Dressler, Miami, Okla.

Application July 1, 1940, Serial No. 93,369

Term of patent 3½ years

To all whom it may concern:

Be it known that I, Adolph C. Dressler, a citizen of the United States, residing at Miami, in the county of Ottawa and State of Oklahoma, have invented a new, original, and ornamental Design for a Fitting for Engine Breather System, of which the following is a specification, reference being had to the accompanying drawing, forming a part thereof.

Fig. 1 is a side elevational view of the fitting for engine breather system, showing my design.

Fig. 2 is an edge elevational view thereof.

Fig. 3 is a plan view of one end thereof; and Fig. 4 is a plan view of the other end thereof.

I claim:

The ornamental design for a fitting for engine breather system, as shown.

ADOLPH C. DRESSLER.
